IMPACT IGNITION DEVICE AND BOMB OR THE LIKE

Application filed May 2, 1932, Serial No. 608,821, and in Germany May 18, 1931.

This invention relates to impact ignition devices and bombs comprising a jacket and a member floating therein and consisting of parts adapted to move with respect to each other by effect of the floating displacement of the whole of said member within said jacket, said parts carrying cooperating striker and primer which are brought into operation to fire the charge on the impact 10 on an obstacle and consequent movement of said parts with respect to each other.

The present invention relates to the organization of said floating member and of parts intended to drive the striker and the 15 primer against each other at the time of impact on an obstacle.

The device of this invention may be embodied in explosive devices of any kind, as projectiles, bombs and the like and it is hereinafter described in connection with a bomb intended to be thrown by hand or by a bomb thrower.

On the annexed drawing a construction of this invention is shown by way of example, 20 in central longitudinal section.

In the illustrated embodiment the device of this invention comprises a jacket consisting of two sections 1 and 2 interconnected by cooperating screwthreaded portions 1" and 2" and providing concave surfaces 1' and 2' at their inwardly facing ends.

Within said jacket 1, 2 is located a floating member which comprises an elongated body 3 and an enlarged head 12 mounted to 35 telescope axially of said body.

In the illustrated embodiment said body consists of a casing which contains an explosive charge 4 and a bottom weight 5 and it provides a central bore 6 in which extends 40 a concentric tube 7 containing a detonator 8-8' and a primer 9.

A perforated tube 10 connected with head 12 extends in the annular space thus provided in the casing 3 and the end of said tube bears 45 on a spring 11 which loosely encircles the tube 7 and abuts on the wall confining the bottom of the annular space within bore 6 of body 3.

The top end of tube 10 has an enlarged 50 and rounded head 12 fast thereon, which is

located in section 2 of the bomb jacket. The head 12 provides a seat 13 concentric with tube 10 in which is located a plunger 14 having the striker 15 fast therein and a spring 16 is located intermediate plunger 14 and 55 the bottom of seat 13.

The top end of plunger 14 provides a curve surface 14' which is forced by spring 16 against the internal surface 17' of a heavy cup member 17 whose flat surface 17" abuts 60 freely on the head 12 while its outer surface 17''' engages the internal surface of the concave end of jacket section 2'.

Said cup member 17 consists with advantage of two sheet metal sections suitably 65 shaped and engaged with each other to provide a space which is filled with a heavy material as lead, to impact a proper weight to said cup.

The radius of the internal surface 17' of 70 cup 17 is materially larger than that of the head of plunger 14 entering it, but is shorter than the radius of outer surface of said cup.

The safety device for the described ignition device consists of a transverse channel 75 member 18 extending through perforations of jacket section 2 and tube 10 intermediate the primer 9 and striker 15; the outer end of said transverse member 18 is articulated by a hook 19 with an outer cap 20 which is positioned on jacket section 2 and is locked thereon by a removable pin 21 extending through cap 20 and jacket section 2.

When the bomb is thrown after the pin 21 removed, the cap 20 releases from the bomb 85 jacket during the bomb fly and it falls down taking the safety transverse member 18 with it; therefore the parts inside the bomb jacket at the time the bomb strikes an obstacle are in the position illustrated in the drawing, they 90 being held in such position by springs 11 and 16. Spring 11 holds the end of body 3 in contact with end 1' of jacket section 1 and tube 10 withdrawn from body 3 with the striker 15 spaced from primer 9 and the top 95 surface 17''' of cup 17 in contact with concave portion 1' of jacket section 1; on the other hand, spring 16 holds the striker 15 with the plunger 14 forced on the internal surface 17' of cup 17.

On impact, if the bomb strikes the obstacle by end portion 1' of its jacket, the cup 17 moves down by its momentum and causes head 12 and plunger 14 with striker firing pin 15 to move down said striker thus striking the primer 9 to ignite detonator 8 and main explosive charge 4.

Should impact take place at end 2' the body 3 with charge 4 and primer 9 are driven towards striker 15.

Finally, when the impact takes place along a line transverse to the bomb axis (that is to axis of tube 10), the internal member comprising the body 3 and head 12 telescoping within the tube 10 is caused to float around the rim 13 of head 12 which bears on the internal surface of jacket section 2, 2'. In this floating motion the body 3 is caused by its end sliding on concave bottom 1' of jacket 1 to telescope along tube 10 and drive the primer 9 towards striker 15, this latter being supported by plunger 14 which rests against cup 17 and therefore against jacket end 2'.

At the same time also cup 17 is caused to effect a floating motion or to move transversely to axis of jacket 1, 2, and owing to concave shape of jacket end portion 2' and of surface 17' of cup 17 which engages the plunger 14 said cup 17 cooperates to drive the striker 15 fast on said plunger against the primer 9.

In the described construction the motion of the floating member has at any time the character of an oscillation around a centre lying at its lighter head that is on rim 13 and therefore the movements of the same are always well defined.

Further in the event of an impact on a line transverse to the bomb axis, the striker 15 is moved towards the primer by the double action of cup 17 on concave bottom 2' of the jacket and of the striker-carrying plunger 14 on the internal concave surface of said cup 17.

Of course the present invention may be embodied in a number of constructions lying within the spirit of appended claims; by way of example the location of striker and primer may be reversed and the explosive charge may be separate from the body 3 or equivalent member of the device.

What I claim as my invention and desire to secure by United States Letters Patent is:—

1. An impact ignition device for bombs and the like comprising in a jacket having concave inwardly facing ends, a body slidably abutting on one of said jacket ends, a head telescoping with said body and having a rim lying within said jacket at a small distance therefrom, a member loosely located intermediate said head and the adjacent concave jacket end, said member having a convex surface engaging the last named jacket end and a concave recess facing said head, a stud extending from said head in said recess of said

member, means operative on said body and head to hold said body and said head with said cooperating member in contact with respective adjacent jacket ends, and a cooperating striker and primer in said body and head. 70

2. An impact ignition device for bombs and the like comprising in a jacket having concave inwardly facing ends, a body slidably abutting on one of said jacket ends, a head telescoping with said body and having a rim lying within said jacket at a small distance therefrom, a member loosely located intermediate said head and the adjacent concave jacket end said member having a convex surface engaging the last named jacket 80 end and a concave recess facing said head, a stud movable in said head and extending therefrom in said concave recess of said member, means holding said stud with its end in contact with the bottom of said concave recess, means operative on said body and head to hold said body and said head with said cooperating member in contact with the respective adjacent jacket end, and a cooperating striker and primer in said body and stud. 85 90

3. An impact ignition device for bombs and the like comprising in a jacket having concave inwardly facing ends, a body slidably abutting on one of said jacket ends, a head telescoping with said body and having a rim lying within said jacket at a small distance therefrom, a member loosely located intermediate said head and the adjacent concave jacket end said member having a convex surface engaging the last named jacket end and a concave recess facing said head, a stud extending therefrom in said concave recess of said member, said stud having an end shaped to a convex surface drawn on a shorter radius than the radius of said concave member recess, means operative on said body and head to hold said body and said head with said cooperating member in contact with the respective adjacent jacket ends, and a cooperating striker and primer in said body and head. 100 105 110

4. An impact ignition device for bombs and the like comprising in a jacket having concave inwardly facing ends, a body slidably abutting on one of said jacket ends, a head telescoping with said body and having a rim lying within said jacket at a small distance therefrom, a member loosely located intermediate said head and the adjacent concave jacket end said member having a convex surface engaging the last named jacket end and a concave recess facing said head, a stud movable in said head and extending therefrom in said concave recess of said member, means holding said stud with its end in contact with the bottom of said concave recess, said stud having an end shaped to a convex surface drawn on a shorter radius than the radius of said concave member recess, means operative on said body and head to hold said body and said head with said cooperating member in con- 120 125 130

- tact with the respective adjacent jacket ends, and a cooperating striker and primer in said body and stud.
5. An impact ignition device for bombs and the like comprising in a jacket having concave inwardly facing ends, a body slidably abutting on one of said jacket ends, a head telescoping with said body and having a rim lying within said jacket at a small distance therefrom, a member loosely located intermediate said head and the adjacent concave jacket end said member having a convex surface engaging the last named jacket end and a concave recess facing said head, said member consisting of a sheet metal box and a filling of heavy material, a stud extending from said head in said recess of said member, means operative on said body and head to hold said body and said head with said cooperating member in contact with the respective adjacent jacket ends, and a cooperating striker and primer in said body and head.
6. An impact ignition device for bombs and the like comprising in a jacket having concave inwardly facing ends, a body slidably abutting on one of said jacket ends, a head telescoping with said body and having a rim lying within said jacket at a small distance therefrom, a member loosely located intermediate said head and the adjacent concave jacket end said member having a convex surface engaging the last named jacket end and a concave recess facing said head, a stud movable in said head and extending therefrom in said concave recess of said member, means holding said stud with its end in contact with the bottom of said concave recess, said stud having an end shaped to a convex surface drawn on a shorter radius than the radius of said concave member recess, means operative on said body and head to hold said body and said head with said cooperating member in contact with the respective adjacent jacket ends, said member comprising a sheet metal box and a filling of heavy material, and a cooperating striker and primer in said body and stud.
7. An impact ignition bomb comprising in a jacket having concave inwardly facing ends, a body slidably abutting on one of said jacket ends, said body comprising a casing and an explosive charge therein, a head telescoping with said body and having a rim lying within said jacket at a small distance therefrom, a member loosely located intermediate said head and the adjacent concave jacket end said member having a convex surface engaging the last named jacket end and a concave recess facing said head, a stud extending from said head in said recess of said member, means operative on said body and head to hold said body and said head with said cooperating member in contact with the respective adjacent jacket ends, and a cooperating striker and primer in said body and head.
8. An impact ignition bomb comprising in a jacket having concave inwardly facing ends, a body slidably abutting on one of said jacket ends, said body comprising a casing and an explosive charge therein, a head telescoping with said body and having a rim lying within said jacket at a small distance therefrom, a member loosely located intermediate said head and the adjacent concave jacket end said member having a convex surface engaging the last named jacket end and a concave recess facing said head, a stud movable in said head and extending therefrom in said concave recess of said member, means holding said stud with its end in contact with the bottom of said concave recess, means operative on said body and head to hold said body and said head with said cooperating member in contact with the respective adjacent jacket end, and a cooperating striker and primer in said body and head.
9. An impact ignition bomb comprising in a jacket having concave inwardly facing ends, a body slidably abutting on one of said jacket ends, said body comprising a casing and an explosive charge therein, a head telescoping with said body and having a rim lying within said jacket at a small distance therefrom, a member loosely located intermediate said head and the adjacent concave jacket end said member having a convex surface engaging the last named jacket end and a concave recess facing said head, a stud extending from said head in said concave recess of said member, said stud having an end shaped to a convex surface drawn on a shorter radius than the radius of said concave member recess, means operative on said body and head to hold said body and said head with said cooperating member in contact with the respective adjacent jacket ends, and a cooperating striker and primer in said body and head.
10. An impact ignition bomb comprising in a jacket having concave inwardly facing ends, a body slidably abutting on one of said jacket ends, said body comprising a casing and an explosive charge therein, a head telescoping with said body and having a rim lying within said jacket at a small distance therefrom, a member loosely located intermediate said head and the adjacent concave jacket end said member having a convex surface engaging the last named jacket end and a concave recess facing said head, a stud movable in said head and extending therefrom in said concave recess of said member, means holding said stud with its end in contact with the bottom of said concave recess, said stud having an end shaped to a convex surface drawn on a shorter radius than the radius of said concave member recess, means operative on said body and head to hold said body and said head with said cooperating member in contact with the respective adjacent jacket ends, and a cooperating striker and primer in said body and head.

body and said head with said cooperating member in contact with the respective adjacent jacket ends, and a cooperating striker and primer in said body and stud.

- 5 11. An impact ignition bomb comprising
in a jacket having concave inwardly facing
ends, a body slidably abutting on one of said
jacket ends, said body comprising a casing and
an explosive charge therein, a head telescoping
10 with said body and having a rim lying
within said jacket at a small distance there-
from, a member loosely located intermediate
said head and the adjacent concave jacket end
15 said member having a convex surface engag-
ing the last named jacket end and a concave
recess facing said head, said member con-
sisting of a sheet metal box and a filling of
heavy material, a stud extending from said
20 head in said recess of said member, means op-
erative on said body and head to hold said
body and said head with said cooperating
member in contact with the respective adjac-
ent jacket ends and a cooperating striker and
25 primer in said body and head.

12. An impact ignition bomb comprising
in a jacket having concave inwardly facing
ends, a body slidably abutting on one of said
jacket ends, said body comprising a casing
and an explosive charge therein, a head tele-
30 scoping with said body and having a rim lying
within said jacket at a small distance there-
from, a member loosely located intermediate
said head and the adjacent concave jacket
35 and said member having a convex surface en-
gaging the last named jacket end and a con-
cave recess facing said head, a stud movable
in said head and extending therefrom in said
concave recess of said member, means holding
40 said stud with its end in contact with the bot-
tom of said concave recess said stud having
an end shaped to a convex surface drawn on
a shorter radius than the radius of said con-
cave member recess, means operative on said
45 body and head to hold said body and said
head with said cooperating member in contact
with the respective adjacent jacket ends, said
member comprising a sheet metal box and a filling
of heavy material and a cooperating
50 striker and primer in said body and stud.

In testimony,

In testimony whereof I have signed my name to this specification

GREGORIO SCAGLIA
